UNITED STATES PATENT OFFICE.

HENRY PLETSCH, OF CHICAGO, ILLINOIS, ASSIGNOR TO JUDD LAUNDRY MACHINE COMPANY, OF CHICAGO, ILLINOIS, A CORPORATION OF DELAWARE.

CLOTHES-WRINGER.

1,216,490.

Specification of Letters Patent.

Patented Feb. 20, 1917.

Application filed March 31, 1913. Serial No. 757,935.

To all whom it may concern:

Be it known that I, HENRY PLETSCH, a citizen of the United States, and a resident of Chicago, county of Cook, and State of Illinois, have invented certain new and useful Improvements in Clothes-Wringers, of which the following is a full, clear, and exact description.

The invention relates to clothes wringers and more particularly to power operated clothes wringers. The improvement seeks to provide simple and effective means for guarding the wringer rolls so that the operator's fingers cannot be caught between the power driven rolls and the invention consists in the features of improvement herein-after set forth, illustrated in the preferred form in the accompanying drawings and more particularly pointed out in the appended claims.

In the drawings, Figure 1 is a view in elevation of a wringer with the improved safety guards applied thereto. Fig. 2 is a vertical cross section of the same.

The wringer frame comprises, as usual, side posts 1 connected at their upper ends by a cross-bar 2 and at their lower ends by a cross-bolt 3. The wringer rolls 4 are mounted on shafts 5 and the latter are journaled in suitable bearings mounted in ways formed in the side posts 1 of the frame. As usual, springs 6 engage the bearings for the upper wringer roll. The ends of a cross-bar 7 engage the upper ends of the springs and are in turn engaged by the adjusting screws 8. The wringer is provided with a reversible drip board 9 having slotted brackets 10 fixed to its ends and by which the drip board is mounted upon the cross-bolt 3. Metal flanges 11 fixed to the ends of the drip board are arranged to engage the lower ends of U-shaped metal brackets 12 that are fastened to the inner faces of the side posts 1. The board can be reversed in usual manner to deflect the drip water in one or the other direction.

The parts thus far described may be of any usual or suitable construction and suitable means may be provided for driving the wringer rolls in opposite directions from a motor.

In placing the clothes in the bite of the wringer rolls, the operator's fingers are brought closely adjacent the same. To prevent them from being caught in the power driven rolls, upper and lower safety guards

are arranged on one side of and above and below the bite of the rolls, so that the operator's fingers cannot be readily brought in contact therewith. But the arrangement is such that clothes may be readily passed into the bite of the rolls. To prevent the binding of the clothes between the guards, one of the guards, and preferably the upper one, is free to yield to and from the other and, in order that the clothes may be passed through the wringer in opposite directions, the safety guards are arranged on opposite sides of the rolls and are shiftable into and out of operative position, so that the safety guards on the exit side of the rolls can be moved out of the way.

The safety guards preferably comprise upper and lower rolls 13 and 14 formed of wood or other suitable material and provided with pintles 15 at their ends and by which the guard rolls are journaled in upper and lower pairs of arms 16 and 17. In the preferred form shown, the pairs of arms are connected by wooden cross strips 18 and 19, the cross strip 18 between the upper pairs of arms 16 being arranged immediately above the upper safety guard roll 13 and the cross-bar 19 being arranged immediately below the lower safety guard roll 14. These bars and the pairs of arms form swinging, U-shaped supports for the safety guard rollers.

The upper ends of the arms 17 are pivotally mounted upon outwardly projecting lugs 20 on the upper ends of the U-shaped brackets 12 and the lower ends of the arms 17 are provided with laterally projecting stop lugs 21 which are arranged to engage the outer faces of the side posts 1. The arms 16 of the U-shaped support for the guard roller 13 are connected to the inner faces of the side post 1 by pivot pins or studs 22 and the lower ends of these arms are provided with laterally projecting stop lugs 23 which are arranged to engage the upper ends of the arms 17.

A pair of guards are arranged on each side of the wringer, but, in operation, the guards and the supports therefor on the exit or discharge side of the wringer rolls are swung upwardly out of the way, as shown at the right in Fig. 2, so that they will not interfere with the free passage of the clothes from the wringer. To hold the guards in this inoperative position, one of the side posts 1 of the frame is provided

with spring clips or catches 24. Each of these spring clips is arranged to engage one of the arms 17 of the support for the corresponding lower guard roll and thus hold it in elevated, inoperative position. In this position, the ends of the arms 17 engage the supporting arms 16 of the upper guard roll and hold it in raised, inoperative position.

19 The safety guards are shown in operative position on the left hand side of Fig. 2. As shown, the lug 20 whereon the support for the lower guard is mounted, projects outwardly beyond the side faces of the posts 1 so that the support for the lower guard hangs vertically in position below the pivotal points of support. The lower guard is thus held in this position and its movement toward the wringer rolls is limited by the 20 engagement of the lugs 21 on the arms 17 with the outer faces of the side posts 1, as shown in Fig. 1. Furthermore, in this position, the lower ends of the arms 17 engage notches or seats 25 in the flanges 11 of the 25 reversible drip board and lock the same in position.

The position of the upper guard roll is determined and its movement toward the wringer rolls is limited by the engagement 30 of the lugs 23 of the arms 16 with the upper ends of the arms 17. In this position, the arms 16 of the support for the upper guard are inclined outwardly to a slight extent from their pivots 22. By reason of this arrangement, the upper guard is free to yield or rise vertically if the clothes bunch up between the guards, so that the latter will not interfere with the free passage of the clothes through the wringer. The arrangement is 35 such that the guards will not interfere with the ready engagement of the clothes with the wringer rolls, but are sufficiently close together in operative position to prevent the operator's fingers from coming in contact 40 with the wringer rolls. Inasmuch as the frame or pivoted arms which sustain the upper safety guard 13 are pivoted to the main frame at a distance above the journals 45 of the wringer rolls, the main frame serves to hold the safety guard 13 so that it will 50 resist combined vertical and inward pressure and will yield under combined vertical and outward pressure. Hence, as the clothes are drawn between the wringer rolls, any 55 excess mass of clothes entering between the guard rolls 13 and 14 will tend to lift the upper guard roll 13, swinging it upwardly and outwardly, but when the operator's hand, in pushing the clothes toward the 60 wringer rolls, contacts with the upper guard roll 13 and in so doing exerts an upward and inward pressure upon the guard roll, this guard roll will resist the movement of 65 the operator's hand and prevent it passing with the clothes into the bite of the wringer

rolls. The upper guard roll thus serves as a positive and constant warning to the operator against permitting his fingers to pass between the wringer rolls. The guards are associated with the reversible drip board in such a way that they can only be lowered to operative position on the entrance side of the wringer, and in operative position, the support for the lower guard locks the drip board in proper position. For example, if 70 the parts are arranged as shown in Fig. 2, the guards on the left hand side of the wringer must be raised to inoperative position before the drip board can be reversed and the latter must be reversed before the 75 guards on the right hand side can be lowered to operative position.

It is obvious that numerous changes may be made in the details set forth without departure from the essentials of the invention 80 as defined in the claims.

I claim as my invention:—

1. In a clothes wringer, the combination 90 with the frame and the wringer rolls mounted thereon, of a pair of safety guards movably mounted on said frame to shift into and out of operative position on one side of and above and below the bite of said rolls, one of said guards, in operative position, being free to move from the other. 95

2. In a clothes wringer, the combination 100 with the frame and the wringer rolls mounted thereon, of upper and lower safety guard rolls movably mounted on the frame and arranged to shift into and out of operative position on one side of said wringer rolls, said upper safety guard roll, in operative position, being free to yield and move from said lower guard roll.

3. In a clothes wringer, the combination 105 with the frame and the wringer rolls mounted thereon, of upper and lower safety guards pivotally mounted on said frame to swing into and out of operative position on one side of and above and below the bite of said 110 wringer rolls, one of said guards being free to move from the other guard to increase the gap between the same, and a catch for holding said guards in inoperative position.

4. In a clothes wringer, the combination 115 with the frame and the wringer rolls mounted thereon, upper and lower pairs of arms pivotally mounted at their upper ends at the sides of said frame, upper and lower safety guards carried respectively by said 120 pairs of arms and arranged to swing therewith into and out of operative position on one side of and above and below the bite of said wringer rolls, one of said guards being free to move from the other. 125

5. In a clothes wringer, the combination 130 with the frame and the wringer rolls mounted thereon, upper and lower pairs of arms pivotally mounted at their upper ends at the sides of said frame, upper and lower

- safety guards carried respectively by said pairs of arms and arranged to swing therewith into and out of operative position on one side of and above and below the bite of 5 said wringer rolls, said arms having stop lugs for limiting the movement of said guards toward said wringer rolls and a catch for holding said guards in raised, inoperative position.
- 10 6. In a clothes wringer, the combination with the frame and the wringer rolls mounted thereon, of upper and lower U-shaped supports pivotally mounted at their upper ends on one side of said frame, upper and 15 lower safety guard rolls journaled in said supports and movable therewith into and out of operative position on one side of said wringer rolls, said upper guard roll being free to move from said lower guard roll to 20 increase the gap between the same and means for holding said frames and guard rolls in raised, inoperative position.
7. In a clothes wringer, the combination with a main frame and wringer rolls mounted therein, of a safety guard arranged in 25 front and above the meeting line of said wringer rolls, a movable frame for sustaining said guard in a manner permitting it to shift into and out of operative position, and 30 means for holding said guard and movable frame rigidly against combined vertical and inward pressure, said holding means permitting said guard to yield under combined vertical and outward pressure.
- 35 8. In a clothes wringer, the combination with a main frame and wringer rolls mounted thereon, of two pairs of safety guards each comprising upper and lower guard members arranged in operative position above and below the bite of said wringer 40 rolls, one pair of said guard members being at the front and the other pair at the back of said main frame, supports for said guard members pivotally mounted on said main frame, said upper and lower guard members 45 being shiftable with said supports into and out of operative position, and means for maintaining one pair of said guard members in operative position and the other pair in 50 inoperative position.
9. In a clothes wringer, the combination with a main frame and wringer rolls mounted therein, of a safety guard arranged in front of the upper wringer roll, a movable frame for sustaining said guard, said movable frame being pivoted at its upper end to the main frame above the journals of the 55 wringer rolls, and means for holding said movable frame and safety guard rigidly against combined vertical and inward pressure but permitting said guard to yield under combined vertical and outward pressure, and a guard arranged beneath said first mentioned guard and in advance of the 60 wringer rolls.
